[57] ABSTRACT

A smoke filtering device for smoking tobacco including a two part receptacle, an inlet to the receptacle, an outlet from the receptacle, a porous filter in the inlet, a porous filter in the outlet, a liquid filter in the receptacle and an additional porous filter in the receptacle above the surface of the liquid filter.

SMOKE FILTERING DEVICE

This invention relates to a smoke filtering device for use with various smoking articles such as cigars, cigarettes, and the like. More particularly, this invention relates to a smoke filtering device which includes a plurality of filters of different types.

BACKGROUND AND OBJECTS

The prior art has taught many types of devices for use with smoking tobacco for the purpose of filtering the smoke associated therewith. These devices have included the quite common filters integral with the cigarette, and have also included devices to which the cigarette is attached. This latter type of device may include a filter in the mouth piece, or route the smoke through a series of filters.

However, these devices have had associated therewith numerous drawbacks such as the necessity for frequent changing of the filter, or refilling of the liquid if a liquid filter is used.

Therefore, a primary object of this invention is to overcome the difficulties associated with prior art smoking devices.

Still another object of this invention is to provide a smoke filtering device which includes a plurality of filters.

Yet another object of this invention is to provide a smoke filtering device which includes different types of filters.

Still a further object of this invention is to provide a smoke filtering device which includes a combination of a liquid and porous filters.

Yet a further object of this invention is to provide a smoke filtering device which includes a liquid filter having a perfumed liquid therein.

Yet another object of this invention is to provide a smoke filtering device utilizing a small, two part receptacle.

These and other objects and advantages of this invention will become apparent when considered in light of the following description and claims when taken together with the accompanying drawings in which:

FIG. 1 is a sectional view of the smoke filtering device of this invention;

FIG. 2 is a left end view of the device of FIG. 1;

FIG. 3 is a top plan view of the device shown in FIG. 1.

DESCRIPTION OF THE INVENTION

Referring now to FIG. 1, a receptacle generally designated 10 is shown as having a top portion 12 and a bottom portion 14. The top portion 12 and bottom portion 14 are connected by a friction fit as indicated at 16. This connection should be fluid tight to prevent drawing air therethrough or spilling of liquid therefrom.

Passing through the top portion 12 is an L-shaped inlet member 18 having a depending portion 20 which extends toward the bottom of portion 14 and terminates short thereof. Positioned within portion 20 of inlet 18 is a porous filter 22 which is retained in portion 20 by a friction fit.

The bottom portion 14 of the receptacle 10 has therein a liquid 24. The portion 20 of inlet 18 extends below the surface of liquid 24 so that smoke passing

through the inlet 18 is bubbled through the liquid 24. Liquid 24 may be of any suitable composition such as water or the like, and serves to filter and cool the smoke passing therethrough. Additionally, liquid 24 may include a perfuming substance which will impart a pleasing aroma to the smoke passing therethrough.

Positioned within the top portion 12 of the receptacle 10, and substantially filling the top portion 12, is an additional porous filter medium 26. This filter may be of the same material as that of filter 22, or it may be different.

Extending from the upper surface of the top portion 12 and at an acute angle thereto is an outlet 28 having a mouth piece 30 secured thereto. The mouth piece 30 is of the usual construction as to enable a comfortable fit in the mouth of the user. Within the outlet 28 is another porous filter 32. This filter 32 may be of the same material as that of filters 22 and 26 or may be different therefrom.

In use, a cigarette or other smoking article C is held in inlet 18 by a frictional engagement therewith. The user places the mouth piece 30 in his mouth, and by drawing through the mouth piece in the usual manner, the smoke from the cigarette C passes through the inlet 18 to the filter 22. This provides a preliminary filtering of the smoke.

Next, the smoke passes through the liquid filter 24 where it is cooled, and if desired, is perfumed. The smoke bubbles out of the liquid 24 and passes next through filter 26. Finally, the smoke passes through filter 32 and mouth piece 30 into the mouth of the user.

The filters 22, 26 and 32 may be either a foam type, a ceramic type, or a fibrous type of filter, and their porosity and filtering capabilities could be made to suit the wishes of the user. Suitable filter materials would include cellulosic fibers, synthetic resin foams such as polyurethanes or polystyrenes, of any of the conventional porous ceramics.

It should be noted that the filtering device of this invention could be made quite small, approximately the size of a pack of cigarettes, and in such a manner as to be carried about by the user without the incumbrances normally associated with prior art types of filters.

Furthermore, this invention provides the advantage that by utilizing the plurality of filters, the filters would not need to be changed as frequently as a number of prior art types.

By utilizing this invention, one would still gain the satisfaction of smoking, but with substantially reduced health hazards.

While this invention has been described, it will be understood that it is capable of further modification, and this application is intended to cover any variations, uses and/or adaptations of the invention following in general, the principle of the invention and including such departures from the present disclosure as come within known or customary practice in the art to which the invention pertains, and as may be applied to the essential features hereinbefore set forth, as fall within the scope of the invention or the limits of the appended claims.

What is claimed is:

1. A smoke filtering device for tobacco including:
  - a receptacle having an upper half and a lower half,

- b. said upper half and said lower half being removably secured together and of substantially equal size,
- c. an inlet to said receptacle including a tobacco receiver, said inlet comprising conduit means extending through said upper half in sealing engagement therewith and opening into said lower half and extending downwardly to closely adjacent the bottom of said lower half of said receptacle,
- d. an outlet conduit means for said receptacle in said upper half only and supporting a mouthpiece,

5

- e. said lower half of said receptacle filled with a liquid filter to substantially above the opening of said inlet conduit means and below said upper half,
- f. a first porous filter plug in said inlet conduit extending below the level of said liquid filter,
- g. a second porous filter plug in said outlet conduit adjacent the top of said receptacle, and
- h. a porous foam filter substantially filling said upper half of said receptacle and having a volume at least equal to the volume of said liquid filter.
